UNITED STATES PATENT OFFICE.

ISAAC E. BENNETT, OF NEWTON, IOWA.

HARNESS-BUCKLE.

SPECIFICATION forming part of Letters Patent No. 398,372, dated February 26, 1889.

Application filed November 6, 1888. Serial No. 290,139. (No model.)

To all whom it may concern:

Be it known that I, ISAAC E. BENNETT, a citizen of the United States of America, and a resident of Newton, in the county of Jasper and State of Iowa, have invented a new and useful Improvement in Harness-Buckles, of which the following is a specification.

My object is to prevent the dangers and annoyances incident to driving-reins and other objects catching on the tongues of buckles that project outward through perforations in the leather straps that are adjustably connected by means of buckles.

My invention consists in the construction and combination of two frames, as hereinafter set forth, in such a manner that the tongue will project inward from one of the frames, and the cross-bars of the frame serve as loops, so that when there is tension on the strap the tongue will be pressed inward through the strap and completely concealed and protected from contact with any extraneous objects.

Figures 1 and 2 of the accompanying drawings show my buckle applied to a leather strap and the strap connected with a ring in the manner halter-straps are attached to a bridle. Fig. 3 is a longitudinal sectional view of Fig. 1. Fig. 4 is a perspective view of the complete buckle.

30 *a* are the side bars, and *b* and *c* the end bars, of a metal frame that may vary in size as desired. The side bars are flattened and widened at their central portions and perforated to admit journals or a cross-bar for the purpose of pivoting another frame thereto. The end bar *b* is also perforated at its center to admit the tongue carried by the mating frame pivoted

to the side bars *a*. The end bar *c* is preferably bent downward at its central portion to admit a leather strap.

40 *d* are the side bars, and *f* and *g* the end bars, of a frame adapted to be pivoted to the inside of the bars *a* by means of projections or journals *h*, formed integral with the bars *d* in such a manner that they can be sprung into the 45 perforations in the bars *a*.

i is a tongue that projects downward from the under side of the bar *f*. The ends of the bars *d* are curved upward, so as to bring the end bar *g* into a higher plane for the purpose 50 of admitting a strap to pass under it and to make it serve as a loop.

55 *m* is a cross-bar formed on or fixed to the central portions of the side bars *d* in such a manner that a strap can be doubled around it, as clearly shown in Fig. 3, to connect the strap with the buckle without stitching or riveting; or a strap may be doubled around and then permanently fastened by means of a rivet or by sewing in a common way, and 60 as required, to connect the buckle with different parts of a harness.

I claim as my invention—

65 The combination of the frame composed of side bars *a* and cross-bars *b* and *c*, said bar *b* provided with an aperture, and the frame composed of the side bars *d*, the end bar *f*, having a tongue on its under side, the bar and loop *g*, and a cross-bar, *m*, substantially as shown and described.

ISAAC E. BENNETT.
